UNITED STATES PATENT OFFICE.

TRUMAN W. POST, OF NEW YORK, N. Y., ASSIGNOR TO WILLYS CORPORATION, OF
TOLEDO, OHIO, A CORPORATION OF DELAWARE.

HEADLIGHT.

1,423,253.

Specification of Letters Patent. Patented July 18, 1922.

Application filed January 15, 1917. Serial No. 142,344.

To all whom it may concern:

Be it known that I, TRUMAN W. Post, a citizen of the United States, residing at the city of New York, in the borough of Manhattan and State of New York, have invented certain new and useful Improvements in Headlights, of which the following is a full, clear, and exact description.

This invention relates to automobile headlights and more particularly to a headlight in which the horizontal beam of light may be shifted so that it is inclined downwardly, thereby preventing the rays of light striking an approaching driver or pedestrian and causing the blinding glare, which so seriously impairs the vision.

One object of the invention is to provide a headlight of this character, in which the entire beam of light may be deflected from its horizontal to an inclined position by means of a movable reflector which can be angularly displaced through a fixed arc by simple electromagnetic mechanism.

Another object of the invention is to provide a tilting reflector, which is positively locked against inadvertent movement or rattling when either in its horizontal or tilted position.

A further object of the invention is to provide a headlight of this character, in which the operating mechanism for tilting the reflector may be initially adjusted after the casing or shell of the lamp has been fixed to the vehicle to compensate for any inaccuracies in the angular position of the casing.

With these and other objects in view, which will be apparent from the detailed description hereinafter to follow, the invention consists of the combinations and constructions which will be hereinafter described, and particularly pointed out in the appended claims.

In the accompanying drawings, Figure 1 is a vertical section through a headlight constructed in accordance with the principles of the invention; and

Figure 2 is a detail of the electromagnetic operating mechanism.

As is the usual construction, the headlight shown comprises a shell or casing 1, which is substantially conical in shape, having a cylindrical flange or ring 2, over the open end of which is mounted the lens or pane of

glass 3, the same being secured to a ring 4' by fastening means 5. This ring 4' is slipped over the end of the cylindrical flange 2 and may be held in position by friction or in any other desired manner. The casing 1 is provided with a box-like extension 4, which holds the electromagnetic mechanism for operating the reflector. The structure so far described is adapted to be mounted upon the vehicle by the usual supporting brackets, not shown, so that the casing has no relative movement with respect to the vehicle.

Mounted within the casing 1 is a reflector 6, which reflector can be of any desired contour, but in practice the usual type of parabolic reflector is used. This reflector has secured to it adjacent its outer edge a stiffening ring 7, which carries trunnion pins 8 which pivotally mount the reflector within a ring 9. The ring 9 is of slightly less diameter than the ring 2 and fits within the ring 2, so that the friction between them will hold the ring 9 against inadvertent movement. An electric lamp 11 is mounted in a socket 12 carried by and projecting through the narrow end of the reflector. Preferably, this lamp is positioned so that its filament or point of brightest illumination coincides with the focal point of the parabolic reflector 6.

The normal position of the reflector 6 is shown in full lines in Figure 1, in which position the rays of light from the lamp and reflector are directed in a generally horizontal direction, as is the usual practice with automobile headlights. The reflector, however, due to its pivotal mounting, is adapted to be thrown into its dotted line position, also shown in this view, in which the beam of light from the lamp and reflector, instead of being directed in a generally horizontal direction is projected downwardly at such an angle that it will strike the road in front of the car at a distance of about 30 feet from the car. This deflection of the beam of light is sufficient to prevent the rays from striking the eyes of an approaching driver and causing the blinding glare, which so seriously impairs the vision. Furthermore, when the light is deflected downwardly to illuminate the portion of the road directly in front of the car the eyes of the driver will naturally follow his own light, and for this reason also the

glare of the headlights of an approaching car will not be so apt to blind him.

To tilt the reflector from the full to the dotted line position the electromagnetic mechanism which will now be described, is utilized. This mechanism comprises two solenoids 20 and 21, which are mounted upon a base plate 22. The solenoid 21 has a core 23 which is pivotally connected to a link 25. This link 25 is in turn pivotally connected to a link 26. A link 27, which is secured to the rim of the reflector, is pivoted at the other end to the link 26. As will be clear from Figure 1, the intermediate link 26 is disposed at practically right angles to the links 25 and 27, and therefore when the solenoid is energized to retract the core 23, this link 26 will have a limited angular movement. This angular movement of the link 26 is utilized to release the locking device, as will now be described. To prevent the reflector from shaking or rattling so as to cause a vibratory beam of light to be thrown upon the road, a spring 29 is fastened to the base plate 22, which spring is provided with a hole or slot 30 therein. A pin 31 carried by the link 27 is adapted to fit into the slot 30 when the reflector is in its horizontal or full line position, the pin and spring constituting a locking device which securely holds the reflector against movement. To release the reflector from the lock the link 26 is provided with a heel 33 which rests upon the spring 29 in the normal or unretracted position of the core 23, as shown in full lines in Figure 1. When the core is energized this heel engages and presses the spring 29 downwardly, which will carry the spring away from the pin 31 so that the link 27, and hence the reflector, will be free to move rearwardly with the core 23.

The core 23 also carries a stop pin 34, which engages the front end of the solenoid to limit the throw of the core 23. This pin is so arranged that when it abuts against the solenoid the reflector has been tilted the required amount to cause the desired deflection of the beam of light. A locking device is also provided for holding the core 23 in its retracted position, so that the solenoid need not remain energized. This locking device consists of a pivoted latch 35 mounted upon the base plate 22, the free end of which is adapted to engage in a notch 36 formed in the under face of the core 23. A small spring 37 exerts a pressure upon the latch 35 to maintain it against the bottom of the core 23, so that when the core is retracted and the stop pin 34 engages with the solenoid the free end of the latch 35 will be forced into the notch 36 and the reflector will be held in its downwardly inclined position until the latch 35 has been moved to release the core. The stop pin 34 and

latch 35 also co-operate to hold the reflector from rattling or from having a slight vibratory movement when the car is in motion.

The releasing of the latch 35 is accomplished by electromagnetic means, including the solenoid 20, which is provided with a core 38 which is normally thrown outwardly by a spring 39. To the free end of this core is pivoted a swinging bar 40, the bar being pivoted at its other end to a bracket or support 41 carried by the base plate 22. This bar extends transversely across the latch 35 which, as appears in Figure 1, is inclined upwardly. When, therefore, the solenoid 20 is energized and the bar 40 swung rearwardly, the bar will engage the pivoted latch 35 and press it downwardly until the latch is free of the notch 36, which will permit the reflector to resume its horizontal position under the force of gravity. If it is desired to return the reflector to its normal position positively, a spring may be utilized as shown for example at 42. As the reflector returns to its normal or horizontal position the stop pin or set screw 31 will engage the upturned edge 29' formed upon the spring latch 29. This will prevent further outward movement of the reflector and the set screw or pin 31 will then engage in the slot 30 and lock the reflector in position.

Any desired circuit arrangement can be used for energizing the solenoids 20 or 21, and in Figure 2 a conventional circuit arrangement for this purpose is shown, consisting of a battery 50 and two parallel circuits 51 and 52, which circuits are opened and closed by switches 53 and 54, respectively.

It should be noted that the base plate 22 carries all of the movable parts of the electromagnetic operating mechanism and this plate is slidably mounted in the extension 4 of the shell or casing 1. The lateral position of the operating mechanism may therefore be adjusted, after which the base plate is locked to the casing by means of a thumb nut 55, which is threaded on the end of the screw 56 carried by the base plate, which screw passes through a slot 57 in the wall of the extension 4 of the casing. The purpose of this construction is to permit an initial adjustment of the reflector as it is evident that if the casing 1, is not correctly mounted upon the automobile of the vehicle, the reflector 6 will not assume a horizontal position. However, by moving the base plate 22, which carries the operating mechanism, backward or forward the angular position of the reflector 6 within the casing may be adjusted to a nicety, after which the operating mechanism is locked by means of the thumb nut 55.

I claim:

1. A headlight comprising a casing, a

- pivottally mounted reflector therein, operating mechanism for tilting said reflector, said operating mechanism being bodily movable in said casing to initially adjust the angular 5 position of said reflector.
2. A headlight comprising a casing, a pivottally mounted reflector therein, operating mechanism for tilting said reflector, a support upon which said mechanism is 10 mounted, said support being movably mounted in said casing, and means for locking said support in said casing in any one of a plurality of different positions.
3. In a headlight, the combination of a 15 casing, a pivottally mounted reflector therein, operating mechanism for tilting said reflector, said operating mechanism being bodily adjustable in said casing to vary the angular position of said reflector.
- 20 4. In a device of the class described, the combination of a casing, reflector mounted to tilt therein, means determining the nor-
- mal and tilted limiting positions of said reflector, a single adjustable means for varying both of said positions and means effective whenever operated to move said reflector to either of said positions in a single movement.
5. In a headlight, the combination of a 25 casing, a reflector pivottally mounted therein, means for locking said reflector in its normal upright position, an electro-magnet for releasing said locking means and moving said reflector to a tilted position, means for locking said reflector in its tilted position, an electro-magnet for releasing said second locking means to permit said reflector to return to its upright position, and means for bodily adjusting said locking means relative to said casing for varying the upright 30 and tilted positions of said reflector.

In witness whereof, I subscribe my signature.

TRUMAN W. POST.
